ISAAC E. PALMER, OF MIDDLETOWN, CONNECTICUT, ASSIGNOR TO THE I. E. PALMER COMPANY, OF MIDDLETOWN, CONNECTICUT, A CORPORATION OF CONNECTICUT.

COUCH-HAMMOCK AND BACK-SUPPORT THEREFOR.

1,103,906.

Specification of Letters Patent.

Patented July 14, 1914.

Original application filed September 12, 1910, Serial No. 581,623. Divided and this application filed April 11, 1914. Serial No. 831,817.

To all whom it may concern:

Be it known that I, ISAAC E. PALMER, a citizen of the United States, and a resident of Middletown, in the county of Middlesex and State of Connecticut, have invented an Improvement in Couch-Hammocks and Back-Supports Therefor, of which the following description, in connection with the accompanying drawings, is a specification, 10 like characters on the drawings representing like parts.

This invention relates to couch hammocks and back supports therefor.

This application is a division of my co-pending application Serial No. 581,623, filed 15 September 12, 1910, now Patent No. 1,094,921, dated Apr. 28, 1914, which is in part a division of my application co-pending therewith, Serial No. 568,682, filed June 20 24, 1910, now Patent No. 972,713, dated October 10, 1910, said latter application being a division in part of my application co-pending therewith, Serial No. 547,637, filed 25 March 7, 1910, now Patent No. 972,711, dated October 10, 1910.

In order that the principle of the invention may be readily understood, I have disclosed certain embodiments thereof in the accompanying drawing, wherein—

30 Figure 1 is a side elevation of a couch hammock having a back support applied thereto in conformity with one type of my invention; Fig. 2 is a detail in plan representing one embodiment of means for connecting the upper portions of the back support to the upstanding hammock suspension means; Fig. 3 is a side elevation of one end of a couch hammock having a back support applied thereto in accordance with another 35 type of my invention; Fig. 4 is a side elevation of a form of frame that may be employed in connection with the construction shown in Figs. 1 and 3; Fig. 5 is a side elevation of one end of a couch hammock showing a back support applied thereto in 40 accordance with another form of my invention; Figs. 6, 7 and 9 are similar views of still further forms of my invention; Fig. 8 is a detail on an enlarged scale of a portion of that form of back support shown in Fig. 7; Figs. 10 and 11 are details in side elevation representing certain forms of 45 means for adjustably connecting the lower portion of the back support with the seat

portion of the hammock to vary the angularity of the former, and Fig. 12 is a view in side elevation of the upper portion of the back support shown in Fig. 7.

Referring more particularly to the drawings, the frame or seat of the hammock is indicated at 1 in the several views. The said frame is preferably composed of longitudinal or side and transverse or end members, either metallic or wooden, connected together in a preferably substantially rectangular form, detachably or otherwise. The frame is preferably provided with any suitable seating, such, for example as one formed of wire links or rope or cloth, and if desired, end and side springs may be employed to connect the seating to the frame. Upon the frame may be positioned a mattress if desired.

The hammock is provided with two upturned suspension ends 2—2, said ends singly and also together constituting upstanding hammock suspension means. These ends may be of any suitable character, but are preferably of cloth, which may be individually connected to the hammock frame 50 at its ends, or if desired the hammock may be provided with a cloth or other body underlying or applied in suitable manner to the frame, and of which the upturned ends form a continuation as in the so-called 55 Gloucester type of hammock. The said upturned ends may be provided with spreaders and clew cords or other suitable hammock suspension means.

In accordance with my invention I provide a back support, the upper portions thereof being applied to and preferably being connected to the hammock suspension means and preferably at a fixed height above the seat, and preferably serving as a pivotal 95 support for the effective portion of said back support. I also provide other and adjustable basal, seat-engaging means independent of said upstanding hammock suspension means and coöperating with the 100 lower part of the effective portion of said back support to vary the angularity of said support, said other and adjustable means preferably coöperating directly with the seat portion of the hammock.

In that form of my invention shown in Fig. 1 the back support is represented as provided with a suitable frame 3 of general

U shape and having a cloth or other suitable covering 4 applied or secured thereto. The upper end of said cloth is provided with a hem 5 having therein a spreader 6 secured at the desired elevation or height 5 above the seat portion of the hammock by suitable means, such as screws 7 and thumb nuts 7', indicated also in Fig. 2. As shown in the latter figure, the suspension end of 10 the hammock, to which I have represented the back support as secured, is provided with two vertical series of holes 8, 8 for the reception of the screws 7 and permit vertical adjustment of the upper end of the said 15 back support. In Fig. 1, the lower end of the back support is represented as provided with shoes 9 pivoted to the frame 3, so that their lower faces may rest flatwise upon the side members of the frame with capacity to 20 slide therealong.

The back support shown in Fig. 3 is provided with a frame 10 preferably covered with cloth or otherwise, the upper end of said frame merely resting against the suspension end 2 of the hammock. The lower end of said back support is represented as provided with pins 11 pivoted to the frame of said back support and engaging any desired pair of the series of sockets 12 in the 25 seat or frame 1 of the hammock, thereby 30 adjustably connecting the lower end of the back support to the seat in such manner as to vary the angularity of said back support. In this form of the invention I have represented the mattress 13 as overlying the 35 frame, the head end thereof being supported at an inclination against the back support.

The back support 14 shown in Fig. 5 may be of the general construction shown in 40 Figs. 1, 3 and 4, but is represented with a spreader 15 positioned against the outer face of the suspension end 2 so as to slide up and down thereon, said spreader being secured to the upper end of the back support by a suitable cord 16. The lower end 45 of the frame of said back support is provided with pins 17 pivoted thereto and adapted to be received in the desired sockets 18 ranging longitudinally of the frame, 50 thereby permitting adjustment of both the upper and lower ends of said back support. If desired, the lower end of said back support may have attached thereto a pillow 19.

In Fig. 6, the back support 14 may be 55 similar to that shown in Fig. 5, it having at the lower end pins 17 adapted to enter any desired sockets 18 of a series of sockets, whereby changes in the angle of inclination of the back support may be made. The 60 support may be attached in any suitable manner to the upstanding hammock suspension means. While preferring to provide hooks as hereinafter shown, I may if desired secure the back support flatwise 65 against the suspension end by providing the

back support with a suitable spreader 6 positioned in a suitable hem or fold 5 and may employ bolts 7 with wing nuts 7', said bolts passing through suitable gromet eyes in such suspension end as indicated in 70 Fig. 2, the said eyes being preferably near opposite edges of the suspension end when the back support is applied to one suspension end only.

In Figs. 7, 8 and 12, I have represented 75 another form of my invention. Therein I have represented the provision of means for projecting outward the back support, so that it may fit more snugly the back of the neck of the hammock occupant. In said figures, 80 I have represented the frame as composed of two members 20, 21 which at their meeting ends are each provided with inwardly projecting pins, 22, 23 respectively, the pins of each member bearing upon the other 85 member, as shown, and preventing the collapse of the frame when in use. Preferably the lower frame 21 is provided with a cloth or other flexible covering 24. The upper member of said back support is provided 90 with hooks 25 or other means for suspending it from the upstanding hammock suspension means, as, for example, to one only of the upstanding ends if desired. The frame shown in said Figs. 7, 8 and 12 may underlie 95 or overlie the hammock mattress as desired. In Fig. 7, I have represented it as underlying the mattress 26, here shown as having a pillow 27 secured thereto along one edge only, so that the pillow may be 100 thrown into the full line position or into the dotted line position as desired. It is evident that the said pillow may be attached along its upper edge only to the frame instead of to the mattress.

In Fig. 7, where the lower end of the two-member frame is represented, I have shown the lower member 21 thereof as provided with pins 28 pivoted in eyes as in Figs. 3, 5, etc., and adapted to be received 110 in the desired sockets 29 of series of sockets formed in the seat of the hammock, thereby permitting the inclination of said two-member frame to be changed.

In Fig. 9, I have represented still another form of my invention. Therein I provide a frame 30 generally similar to that shown in Figs. 1, 3 and 5, it being preferably provided with a suitable flexible covering 31. The upper end of said frame 115 or the covering thereof is connected in any suitable manner, as by a flexible strip 32 with a series of hooks 33 adapted to be received upon the upstanding hammock suspension means, as for example upon one 120 only of the suspension ends 2. In said figure, I have represented the hooks as received over the spreader 34. The back support shown in said figure may either underlie 125 or overlie the mattress. I have herein 130

represented it as underlying one end of the mattress 35, here shown as having a pillow 36 connected to its head end.

In Figs. 10 and 11 I have shown several means for adjustably connecting the lower end of the back support with the frame of the hammock. In Fig. 10, the frame 1 is represented as provided with a plurality of sockets 37 to receive pins 38 having eyes 39 in their upper ends engaging the eyes 40 of the lower end of the frame 41 of the back support, the latter preferably having a flexible covering 42.

In Fig. 11, I have represented the lower end of the frame 43 as bent at 44 to provide depending ends 45 adapted to enter the desired sockets 46 in the frame 1. The said sockets are herein represented as flared to permit rocking movement of said ends 45 when the adjustment of the upper end of the back support is slightly altered. By positioning the depending ends 45 in different pairs of sockets 46, the inclination of the frame 43 may be varied.

While the frame shown in the several figures may be of any suitable material, it is preferably of wire, the spreaders when employed being of usual material, such as wood, such spreaders being shown in Figs. 1, 6, 7 and 9.

While I have herein represented the back rest support as applied or attached to one end only of the couch hammock, my invention is not limited to such use thereof, as within the scope of the invention the back support may be so positioned as to extend either transversely or longitudinally of the seat portion of the hammock, which may be of a suitable length to accommodate such longitudinal positioning of said back support. Thus, the said support may be connected to either one or to both of the suspension ends at a suitable distance above the seat portion of the hammock.

Having thus described one illustrative embodiment of my invention, I desire it to be understood that although specific terms are employed, they are used in a generic and descriptive sense and not for purposes of limitation, the scope of the invention being set forth in the following claims.

I claim—

1. A couch hammock comprising a seat, upstanding hammock suspension means, a back support, means for connecting the upper portions of said support to said hammock suspension means above the seat and serving as a pivotal support for the effective portion of said back, and adjustable basal, seat-engaging means coöperating with the lower part of the effective portion of said back support to vary the angularity of the latter.

2. A couch hammock comprising a seat, upstanding hammock suspension means, a

back support, means for connecting the upper portions of said support to said hammock suspension means above the seat and serving as a pivotal support for the effective portion of said back, and adjustable basal, seat-engaging means independent of said upstanding hammock suspension means and directly coöperating with the seat portion of the hammock and with the lower part of said back support, to vary the angularity of the latter.

3. A couch hammock comprising a seat, upstanding hammock suspension means, a back support, means for connecting the upper portions of said support to said upstanding hammock suspension means above the said seat, and other and adjustable basal, seat-engaging means independent of said upstanding hammock suspension means and coöperating with the lower part of said back support to vary the angularity of the lower end thereof.

4. A couch hammock comprising a seat, upstanding hammock suspension means, a back support having a spreader-bar along its upper edge, means for connecting said spreader-bar to said hammock suspension means above the said seat, and other and adjustable basal, seat-engaging means independent of said upstanding hammock suspension means and coöperating with the lower part of said back support to vary the angularity of the lower end thereof.

5. A couch hammock comprising a seat, upstanding, flexible hammock suspension means, a back support, means for adjustably connecting the upper portions of said support to said upstanding hammock suspension means above the said seat and other and adjustable basal, seat-engaging means independent of said upstanding hammock suspension means and coöperating directly with the seat portion of the hammock and with the lower part of said back support to vary the angularity of said back support at the lower portion thereof.

6. A couch hammock comprising a seat, upstanding hammock suspension means, a back support having a spreader-bar along its upper edge, means at the ends of said spreader-bar for connecting said back support to said hammock suspension means above the said seat, and other and adjustable basal, seat-engaging means independent of said upstanding hammock suspension means and coöperating directly with the seat portion of the hammock and with the lower part of said back support, to vary the angularity of said back support at the lower portion thereof.

7. A back support adapted to be connected to the upstanding hammock suspension means and the seat of the couch hammock, said support comprising a back supporting member having means for connect-

ing the upper portions thereof to the up-
standing hammock suspension means above
the seat thereof, said member having other
and adjustable basal, seat-engaging means
adapted to coöperate with the seat of the
hammock to vary the angularity of the lower
end of said member.

In testimony whereof, I have signed my
name to this specification, in the presence of
two subscribing witnesses.

ISAAC E. PALMER.
